UNITED STATES PATENT OFFICE

1,926,461

EVAPORATOR

Franklin G. Slagel, Buffalo, N. Y., assignor to
Fedders Manufacturing Company, Inc., Buffalo,
N. Y., a corporation of New York

Application August 13, 1930. Serial No. 475,030

5 Claims. (Cl. 62—126)

This invention relates to mechanical refrigerating apparatus and more particularly to evaporators.

An object of the invention is to provide an evaporator in which tubes and a header are formed and arranged to form a quick freezing chamber as well as a heat transfer medium for air contacting therewith.

Another object of the invention is to provide an evaporator consisting of a header and tubes which emanate from a small area of the header and are formed to provide a rectangular ice forming enclosure open at only one side.

Still another object of the invention is to provide an evaporator in which a minimum number of tubes are bent and associated with a header to form a freezing chamber open at only one end for the insertion of trays.

Other objects of the invention will appear from the following description taken in connection with the drawing, which forms a part of the specification, and in which:

Fig. 1 is a side elevational view of an evaporator, the header being partially broken away.

Fig. 2 is a front elevational view of the same.

Fig. 3 is a view looking at the bottom of the evaporator.

Referring now to the drawing by characters of reference, 10 represents the header of the evaporator which is preferably formed of sheet metal formed as a cylinder and open at the front end. An end plate 11 seals the open end of the header, and provides the support for control mechanism, within the header, as well as for the refrigerant conduits.

As a means of conducting gasified refrigerant and oil from the header, a tube 12 extends into an outlet opening 13 in the end plate, and a union 14 is secured to the end plate in communication with the opening. The conduit 15 extends from the union to the compressor (not shown). A union 16 is secured to the end plate and communicates with an opening 17 through the plate, a conduit 18 extending from this union to the condenser (not shown). Arranged in the opening 17 is an apertured seat member 19 with which the needle valve 20 is associated, such valve being carried by the open float 21 which is pivotally connected with the end plate by a pin 22. The tube 12 is bent downwardly so that one end extends within the open float and adjacent the bottom wall thereof.

The evaporator is preferably of the flooded type. Liquid refrigerant and oil, either partly or wholly in solution enter the header where the

valve 20 is unseated by the movement of the float when its position is lowered by evaporation of the refrigerant in the header such that the level of the accumulation is below a predetermined level. The float rises with the accumulation and will cause the valve to shut off the flow of incoming refrigerant when the accumulation reaches the desired quantity. Oil and gasified refrigerant move into the open float in the same relative quantity as admitted to the header, and are removed by compressor suction through the outlet tube.

In order to increase the heat transfer surface and to form an ice making chamber, I provide tubes 23, 24 and 25 having their open ends communicating with the interior of the header and projecting through a small area at the rear end thereof. The tubes 23 and 24 are similar and extend in a vertical plane, one depending from each side of the header. The tubes are formed with parallel legs 26 and 27 extending from the rear sides of the header, the legs 26 extending well below the legs 27, and the portion 28 therebetween being bent to form a plurality of loops 80 extending longitudinally of the header. The tube 25 includes two spaced vertical legs 29 which depend from the rear end of the header and below the tubes 23 and 24 and intermediate the legs 26 and 27. The portion 30 of the tube 25, intermediate the legs 29, is bent at an angle and in the form of a plurality of loops which lie parallel with the header. The three tubes bound a space below the header which is open at the front end and thus provide a chamber for receiving pans 90 of water to be frozen.

A sleeve 31 is arranged within the tubes, preferably in intimate contact therewith, and bosses 32 are formed on the interior faces of the sleeves to serve as supports for the trays 33. A plate 34 is carried by the bosses to support one of the trays. The rate of heat transfer provided by this arrangement of tubing and sleeve, insures the water being rapidly frozen. The tubes also serve to transfer heat from air circulating past the exterior of the tube structure.

Although this invention has been described in connection with certain specific embodiments, the principles involved are susceptible of numerous other applications which will readily occur to persons skilled in the art, and the invention is therefore to be limited only as indicated by the scope of the appended claims.

What I claim is:—

1. In an evaporator, a header, means for automatically maintaining a quantity of liquid refrigerant

- erant in the header, and a tube depending from one end of the header and having an intermediate portion formed in loops arranged in a horizontal plane and extending parallel and longitudinally of the header, the ends of said tube being in communication with the liquid in the header. 5
2. In an evaporator, a header, means for automatically maintaining a quantity of liquid refrigerant in the header, a tube depending from each side of the header, each of said tubes being bent to form loops extending longitudinally of the header, and a tube depending from one end of the header and having an intermediate portion formed in loops arranged in a horizontal plane and extending parallel and longitudinally of the header, the ends of the tubes being secured to the header in communication with the liquid in the header. 10
3. In an evaporator, a header, means for automatically maintaining a quantity of liquid refrigerant in the header, a tube depending from each side of the header and bent to form loops extending longitudinally in spaced relation of the header to form a freezing chamber, and a tube depending from one end of the header and bent to form a horizontal loop extending parallel and longitudinally of the header, and adjacent said longitudinally extending loops. 15

4. In an evaporator, a header, means for automatically maintaining a quantity of liquid refrigerant in the header, a tube depending from each side of the header and bent to form loops extending longitudinally in spaced relation of the header to form a freezing chamber, and a tube depending from one end of the header and bent to form a horizontal loop extending parallel and longitudinally of the header, and adjacent said longitudinally extending loops, the ends of said tubes all extending through a small wall area of one end of the header and in open communication with the refrigerant therein. 80
5. In an evaporator, a header, means for maintaining automatically a quantity of refrigerant in the header, a rectilinear shell having a back wall and an open front, said shell disposed below the header to provide a freezing receptacle, and tube means mounted on and covering a major portion of the side and back walls of the shell and having a horizontal loop portion engaging the bottom wall of the shell, said tube means being in communication with the refrigerant in said header. 85
